SEWING MACHINE

Herman Hertzberger, New York, N. Y.

Application December 8, 1941, Serial No. 422,076
In Germany July 3, 1941

3 Claims. (Cl. 112—219)

This invention relates to sewing machines, and more particularly to a novel attachment for sewing machines for automatically disengaging the needle from the work when the machine is stopped.

The device of the invention is particularly designed for use in connection with sewing machines which make about 2000 stitches per minute and more. Usually sewing machines of this type are driven by an electric motor and are used in the textile industry.

Frequently a number of parallel rows of stitches must be sewed on the same goods. Every time a row has been finished the sewing machine must be stopped. Then the worker must disengage the needle from the work before he can start with the next row of stitches. Generally this is done by rotating the balance wheel of the sewing machine, and to this end the worker must remove one hand from the work. The inventor has found that if the time required for sewing an open lining is for instance 54 seconds then 16 seconds are required for disengaging the needle from the work.

In accordance with the invention this drawback is removed. The machine of the invention comprises a device for automatically disengaging the needle from the work after the sewing machine has been stopped or nearly brought to a standstill. Preferably, the device of the invention is actuated by the foot or the knee of the operator so that he can use both hands for holding and moving the work.

Preferably the device of the invention is connected with a switch for switching off the drive motor of the sewing machine. By actuating for instance a foot pedal the switch is first actuated and then the device of the invention is released for disengaging the needle from the work.

In a preferred embodiment of the invention the balance wheel of the sewing machine which is secured to the main drive shaft has a member depending therefrom which may for instance be a stud. This stud is adapted to cooperate with a member such as a plate which is normally below the balance wheel. When the drive motor of the sewing machine is disengaged this plate is lifted to engage the stud. Thus the balance wheel is rotated until the needle is disengaged from the work.

It is accordingly an object of the invention to provide a novel attachment for sewing machines.

Another object of the invention is to provide a device for automatically disengaging the needle

from the work after the sewing machine has been stopped.

A further object of the invention is to provide an apparatus which first switches off the electric drive motor of the sewing machine and then automatically disengages the needle from the work.

These and further objects of the invention will become more apparent when the description proceeds taken in connection with the drawing, wherein:

Fig. 1 is a schematic side view taken from the left-hand side of a sewing machine.

Fig. 2 is a schematic side view taken from the right-hand side of a sewing machine and illustrating the device of the invention.

Referring to the drawing, the sewing machine comprises a main drive shaft 10 bearing a crank 11 connected with connecting rod 12 driving in turn crosshead 13. Crosshead 13 is guided in bearing 14 and bears needle 15, removably secured by screw 16. The work 17 is supported on table 18. Drive shaft 10 has secured thereto wheel 20 driven by electric motor 21 by means of belt 22.

It will be evident that when crank 11 is in any position within the angle indicated at α , needle 15 will be disengaged from work 17. Only when crank 11 is in a position below angle α , needle 15 pierces work 17. In order to disengage the needle from the work it is therefore only necessary to bring crank 11 into any position within angle α .

To this end balance wheel 23 secured to main shaft 10 is provided with stud 24. Preferably, stud 24 is arranged so that it is aligned with crank 11. Stud 24 is adapted to cooperate with plate 25 which is urged downwardly by springs 26, 26. Springs 26, 26 are secured to base 27 supported by a frame work 28. Plate 25 has a depending rod 30 guided in bearing 31. Rod 30 is adapted to be lifted by cam 32 secured to shaft 33. Lever 34 is secured to shaft 33 and has a pin engaging slot 35 in lever 36. The lower end of lever 36 is secured to foot pedal 37 at 38. Pedal 37 has its fulcrum at 40 where it is secured to frame work 28. Spring 41 urges pedal 37 upwards into its dotted position 37a. Switch lever 42 has a lost-motion connection with rod 36 and actuates switch 43; current is conducted to the switch by wires 44. Switch lever 42 carried at its one end a contact segment 53. The current is conducted through wires 44. These wires are connected with wires 51 and 52 leading to terminals 50 and 55.

The operation of my novel device will now be evident. Normally foot pedal 37 is in the dotted position 31a. Cam 32 is in its dotted position 32a and is not in engagement with rod 30. Hence springs 26 are free to pull plate 25 against bearing 31. Motor 21 is energized when the switch lever is in its position indicated at 42a.

When it is desired to stop the sewing machine and to disengage the needle, the operator presses down foot pedal 37a which now moves into the full-line position 31. This causes a downward movement of switch lever 42a for switching off motor 21. Due to the lost-motion connection between rod 36 and crank 34 the latter does not start to move until motor 21 has been switched off. Further downward movement of pedal 37 causes rotation of cam 32a into its full line position 32 which causes lifting of rod 30. Now plate 25 brings stud 24 into the position shown in Figs. 1 and 2.

Plate 25 has a projection 45 which serves the purpose to bring stud 24 out of its dead point.

It will be understood that the device of the invention may easily be attached to any sewing machine.

Various changes and modifications may be made to the details of construction of the invention without departing from the broader spirit and scope thereof, as set forth in the following claims.

I claim:

1. In a sewing machine having a main shaft, an electric motor for driving said shaft, a balance wheel on said shaft, and a needle operatively connected with a said shaft and reciprocated thereby, a switch for said motor, a device for automatically disengaging said needle including an element extending from said balance wheel, a plate normally arranged below said element, a cam arranged to lift said plate on rotation thereof, a foot pedal operatively connected

with said cam by a lost-motion connection and connected with said switch for actuation thereof whereby when said pedal is moved said switch is switched off and said plate is engaged with said element.

2. In a sewing machine having a main shaft, an electric motor for driving said shaft, a switch for said motor, a balance wheel on said shaft, and a needle operatively connected with said shaft and reciprocated thereby, a device for automatically disengaging said needle including a stud on said balance wheel, said stud having a predetermined position, a plate normally arranged below said stud, a spring urging said plate away from said stud, a cam arranged to lift said plate on rotation thereof, a foot pedal, a rod connected with said foot pedal and having a lost-motion connection with said cam, said rod being connected with said switch for actuation thereof, whereby actuation of said pedal causes first switching off of said switch and thereafter rotation of said cam.

3. In a sewing machine having a main shaft, an electric motor for driving said shaft, a switch for said motor, a balance wheel on said shaft, and a needle operatively connected with said shaft and reciprocated thereby, a device for automatically disengaging said needle including a stud on said balance wheel having a predetermined position, a plate normally arranged below said stud and having a projection in its center, a spring for urging said plate away from said stud, a cam arranged to lift said plate on rotation thereof, a foot pedal operatively connected with said cam by a lost-motion connection and connected with said switch for actuation thereof whereby movement of said pedal causes switching off of said switch and lifting of said plate into engagement with said stud.

40 HERMAN HERTZBERGER.
